UNITED STATES PATENT OFFICE.

JOHN QUEEN SLYE, OF WASHINGTON, DISTRICT OF COLUMBIA.

PHYSICAL EXERCISER OR ATHLETIC VEHICLE.

1,287,484.

Specification of Letters Patent. Patented Dec. 10, 1918.

Application filed May 29, 1918. Serial No. 237,204.

To all whom it may concern:

Be it known that I, JOHN QUEEN SLYE, a citizen of the United States of America, residing at Washington, District of Columbia, 5 have invented a new and useful Physical Exerciser or Athletic Vehicle, of which the following is a specification.

This invention relates to an improved toy physical exerciser or athletic vehicle, particularly adapted for children preferably 10 boys.

One of the objects of the invention is to provide a device of this kind, whereby all parts of the body may be brought into 15 action, so that the muscles thereof may be developed.

A further object of the invention is to provide a physical exerciser having a longitudinally movable seat in gear connections with 20 the rear drive axle of the device, whereby motion may be imparted thereto.

A further object of the invention is to provide means to be actuated by the arms of the operator, so that in conjunction with 25 the movable seat, the apparatus may be propelled at a high rate of speed.

A further object of the invention is to provide a physical exerciser, the propelling mechanism of which is actuated in a manner 30 greatly resembling the motions of the body of an operator of a racing canoe, whereby the arms, legs, shoulders and the muscles thereof and those of the body may be developed in a similar manner as those 35 of an operator of a racing canoe.

A further object of the invention is to provide an improved steering mechanism for the apparatus, whereby the operator may steer the same with the feet.

40 A further object of the invention is to provide a physical exerciser of this kind having means whereby the forward part of the canoe may be given a vertical or up and down vibration, resembling that imparted to 45 a canoe body when passing over the waves of the water.

In practical fields the details of construction may necessitate alterations falling within the scope of what is claimed.

The invention comprises further features 50 and combination of parts as hereinafter set forth shown in the drawings and claimed.

In the drawings:—

Figure 1 is a view in perspective of the improved physical exerciser or athletic vehicle 55 constructed in accordance with the invention.

Fig. 2 is a longitudinal sectional view on line 2—2 of Fig. 1.

Fig. 3 is a sectional view on line 3—3 of 60 Fig. 2.

Fig. 4 is a sectional view on line 4—4 of Fig. 2.

Fig. 5 is a detail perspective view of the steering mechanism to be operated by the 65 feet of the operator.

Fig. 6 is a sectional view on line 6—6 of Fig. 2.

Referring more especially to the drawings, 70 1 designates the body of the physical exerciser or athletic vehicle, which may be any conventional shape, preferably of a shape to resemble a canoe or the like. Secured by bolts or the like 2 to the rear under portion of the body is a pair of brackets 3, in bearings of which a drive shaft 4 is mounted. 75 This shaft is provided with cranks 5 and 6. Mounted upon the ends of the shaft 4 are supporting wheels 7, which may be of any suitable construction, preferably provided with pneumatic tires 8. If necessary the supporting wheels may be especially constructed for the device, or they may be bought or purchased from stock. The shaft 4 may be cast from malleable iron and then 85 hardened, or may be machined. For instance the shaft may be bent, and subsequently machined, and its ends capped for the reception of nuts. The brackets 3 are preferably triangular shaped and have 90 bearings 9 for the reception of the crank shaft. The brackets are designed to be cast preferably, but it is to be understood they may be machine made if desired. Also secured by bolts or the like 10 to the bottom 95 of the canoe are forward and rear brackets 11 and 12, which are substantially identical in shape and construction, and are designed

to be constructed in any suitable inexpensive manner, preferably by casting. In front view the bearings 11 and 12 are V-shaped, and their lower parts are provided with 5 transverse portions 13. These transverse portions are provided with guides 14 and 15, for the reception of the racks 16 and 17. These racks may be especially made, or used 10 from stock material. The intermediate or central rack has its teeth 18 upon its upper edge, and its rear end (which is forked as shown at 19) has a link 20 connected thereto. This link is in turn connected to the crank 6 of the drive axle or shaft as shown at 21. 15 The racks 16 have their teeth 22 on their outer edges. The rear ends of the racks 16 are forked as shown at 23, between which the links 24 are connected. These links are in turn connected at 25 to the cranks 5 of the 20 drive axle or shaft 4. Secured to the bottom of the body of the physical exerciser are bearing brackets 26, which may be of any suitable shape preferably as shown. Mounted in bearings of the brackets 26 are vertically 25 disposed shafts 27, which are also mounted in bearings 28 of the inner faces of the sides of the canoe shaped body of the apparatus. The lower ends of the shafts 27 are provided with segment gears 29, to mesh with the 30 teeth 22 of the racks 16. The upper ends of the shafts 27 have secured thereto in any suitable manner as shown at 30 operating handles 31, to be engaged or grasped by the hands of the operator. Oscillating movement 35 may be imparted to said handles, whereby the shafts 27 may be rocked, so that motion may be imparted to the segment gears. It is to be noted that the segment gears will in turn impart reciprocating 40 movement to the racks 16, and owing to their link connections with the rear axle or drive shaft, revoluble movement will be imparted thereto, for driving the supporting wheels, and hence propel the physical exerciser. 45 Secured to the inner faces of the sides of the body of the apparatus, as shown at 32 are bracket guide rods 33. An operator's seat 34 is provided. This seat has a cushion 36 and a cushion back 37. The seat 34 may 50 be so desired, consist simply of the plate 34, the ends of which are provided with depending spaced arms 38. This seat may be cast or made up from sheet metal. Journaled between the depending arms 38 are anti-frictional rollers 39, which are grooved, there 55 preferably being eight in all, two in the front adjacent each side, and two in the rear adjacent each side, so as to engage above and below the bracket guide rods 33, 60 whereby the seat will freely move backwardly and forwardly, in fact will be allowed to reciprocate. The plate 34 has a depending arm 40 in its center, and connected to the lower extremity of this arm

is a link 41. Pivotedly mounted upon a 65 shaft pin 42 carried in bearings depending from the bottom of the apparatus is a segment gear 43, the teeth 44 of which are designed to mesh with the teeth 18 of the central or intermediate rack. This segment 70 gear 43 has a radiating arm 45 extending through an opening 46 in the bottom of the body of the apparatus, and to the extremity of which the link 41 is connected. It is to be observed that as the operator is imparting 75 movement to the shafts 27, a reciprocating movement will also be imparted to the seat, the action of which will transmit movement to the segment gear 43, which in turn will operate the central or intermediate rack 17 80 alternately with the racks 16, thereby assisting materially in rotating the shaft or axle and propelling the physical exerciser. An operator being subjected to these movements 85 of the body and the arms at regular intervals, will materially develop the body and the arms and the muscles thereof.

Side frame bars 47 for the physical exerciser are provided. The forward ends of these frame bars terminate in transverse tubular bearings 48, for the reception of the forward axle 49. The rear ends of the frame bars 47 have bearings 50, in which the rear drive axle or shaft is mounted. The frame bars 47 have bearings 51 for the shaft 52, 95 which is designed to rotate, as will be hereinafter set forth. A disk 53 is mounted upon and rotatable with the shaft 52. The disk is eccentrically mounted on the shaft which is also provided with a gear 54. The disk 100 is disposed with relation to the body of the apparatus, so that its peripheral edge will engage the body. The bottom of the body on each side where the disk engages the bottom is provided with spaced guide flanges 105 55, so as to prevent excessive lateral play of the body with respect to the disk. The outer ends of both tubular bearings 48 are provided with forks 56. The front supporting wheels 57, which may be especially 110 made or purchased from stock, are mounted upon and rotatable with the stub axles 58, which are mounted in bearings 59. The inner ends of these bearings 59 are provided with forks 60. The forks 56 and 60 are 115 pivoted together respectively by the bolts 61 and 62, which are axially aligned. The inner ends of the stub shafts 58 have gears 63, which mesh with the bevel gears 64 loose upon the bolts 61. The gears 64 in turn 120 mesh with the gears 65 on the outer ends of the front axle or shaft 49. Consequently it will be observed that when the supporting wheels 57 rotate, motion will be transmitted to the shaft 49 and hence to the gear 66. 125 The tubular bearings have rearwardly extending spaced arms 67 carrying a stub shaft 68, which is provided with a gear 69. The

gear 66 meshes with 69, which in turn drives the gear 54, and since revoluble movement is imparted to the shaft 52 by this train of gears, the eccentrically mounted disk 53 will 5 impart vertical movement or vibration to the body of the physical exerciser. This vertical vibration will be slow and gradual so as to greatly resemble the usual movement of a canoe body when passing over the 10 waves when the same is paddled.

The uppermost of the forks 60 have tubular extensions 70, for the reception of the elongated bolts 62, and for the purpose of steering the front supporting wheels 57. 15 The upper ends of the tubular extensions have inwardly extending arms 71, to which the link rods 72 are connected as at 73. Fixed transversely of the canoe body of the apparatus and in the sides of the body 20 is a shaft 74, on which the steering members 75 are pivotally suspended, the spaced collars 76 acting to retain the steering members in their proper central position, and to the steering members the link rods 72 are connected as shown at 77. The lower portions 25 of the steering members terminate in feet engaging shoes 78, to be engaged by the feet of the operator. The tubular extensions 70 have rearwardly extending arms 79, between 30 which a link bar 80 is connected. The operator of the apparatus by placing his feet in the shoes 78, and oscillating them backward and forward, one in one direction and the other in the opposite direction, or keeping 35 the steering members steady, the front supporting wheels 57 may be steered in any direction desired. The tubular extensions 70 pass through the openings 81 of the forward part of the sides of the body of the 40 apparatus. A front seat 82 is fixed between the sides of the body 1 of the apparatus. It is to be noted that the forward part of the body is not fixedly connected to any of the operating mechanism, thus it will be observed 45 that the body will vertically vibrate. The body may be constructed of any suitable material, wood or the like, in fact preferably constructed of any suitable sheet metal, for instance heavy sheet tin or comparatively thin galvanized sheet iron, and may be painted or otherwise decorated.

The invention having been set forth what is claimed as new and useful is:—

1. The combination with a rear drive axle 55 having supporting wheels, of a body pivotally mounted on said axle, a forward non-driving axle having wheels, and means geared to the forward non-drive axle for imparting slow gradual vertical vibrations to 60 the body.

2. The combination with a rear drive axle having supporting wheels, of an operating mechanism for driving the axle, a body pivotally mounted on said axle, a forward non-

drive axle having supporting wheels, and a 65 rotating member geared to the forward axle for imparting vertical vibrations to the body.

3. The combination with forward and rear drive axles having supporting wheels thereon, of a body pivotally mounted upon the rear drive axle, a frame for said axles, a shaft mounted in bearings of said frame, gear connections between said shaft and the forward axle, and an eccentric on said shaft, 70 whereby a vertical vibration may be imparted to the body.

4. The combination with forward and rear drive axles having supporting wheels thereon, of a body pivotally mounted upon the 80 rear drive axle, a frame for said axles, a shaft mounted in bearings of said frame, gear connections between said shaft and the forward axle, and an eccentric on said shaft, 75 whereby a vertical vibration may be imparted to the body, and means on the bottom of the body engaging on each side of the eccentric to prevent excessive lateral movement of the body.

5. The combination with forward and rear 90 drive axles and supporting wheels therefor, of a body pivotally mounted upon the rear axle, and means actuated by the forward axle to impart vertical vibrations to the body, and means actuated by the body and 95 arms of the operator and geared to the rear axle for driving the same.

6. The combination with forward and rear supporting wheels, of a crank shaft for the rear wheels of a body pivotally mounted 100 upon said crank shaft, the under part of the body having guide bearings, alternately reciprocating racks mounted in the guide bearings and having link connections with the cranks of the crank shaft, a reciprocating operator's seat mounted in the body, a segment gear linked to the seat and in gear with one of the racks, and rocking shafts 105 geared to the other racks and having rowing handles, whereby reciprocating movement 110 may be imparted to the other racks.

7. The combination with a body, of rear supporting wheels therefor, a forward axle provided with stub shafts, bearings for the stub shafts having tubular vertical extensions, a link connection between said extensions, the upper ends of said extensions having inwardly extending arms, rods connected to said arms, a transverse fixed shaft on the body, steering members pivotally suspended 115 on said shaft to be engaged by the feet of the operator and being connected to said rods.

8. In a toy canoe physical exerciser, the combination with a frame, of forward and rear drive axles, a body pivotally mounted on the rear drive axle, a train of gears mounted in said frame and operated by the 125

forward axle, means operated by the train of gears to impart vertical vibrations to the body, and flanges carried by the body engaging on each side of said means to prevent excessive lateral movement of the body.

9. The combination with a rear drive axle having supporting wheels, of an operating mechanism for driving the axle, a body pivotally mounted on said axle, a forward non-drive axle having pivotal supporting wheels, a rotating member geared to the forward

axle for imparting vertical vibrations to the body, and manual operated means connected to the pivotal supporting wheels for steering the machine.

15

In witness whereof, in the presence of two witnesses, the inventor's signature is hereunto affixed.

JOHN QUEEN SLYE.
